LOCKER

Robert L. Propst, 2347 Londonderry, Ann Arbor, Mich.
48104, and James O. Kelley, 203 Woodingham Court,
Saline, Mich. 48176

Filed Oct. 26, 1970, Ser. No. 25,638

Term of patent 14 years

Int. Cl. D6—04

U.S. Cl. D6—150

FIG. 4

FIG. 3

FIG. 6

FIG. 5

FIG. 1 is a perspective view of a locker, showing our design with its door open;

FIG. 2 is a perspective view of the locker with its door closed;

FIG. 3 is a side view of the locker;

FIG. 4 is a rear view of the locker;

FIG. 5 is a cross section taken along plane V—V of FIG. 1, with the door removed;

FIG. 6 is a plan view of the locker.

Both the left and right sides of the locker are identical, one side being a mirror image of that side which is shown in FIG. 3.

We claim:

The ornamental design for a locker, substantially as shown and described.
